Primary Examiner—Stella Reid*Assistant Examiner*—Mark A. Goodwin*(74) Attorney, Agent, or Firm*—Akin Gump Strauss Hauer & Feld, LLP(57) **CLAIM**

The ornamental design for a carton with handle, as shown and described.

DESCRIPTION

FIG. 1 is a side perspective view of a carton with handle showing our new design;

FIG. 2 is a front view thereof;

FIG. 3 is right side view thereof;

FIG. 4 is a rear view thereof;

FIG. 5 is a left side view thereof;

FIG. 6 is a top plan view thereof;

FIG. 7 is a bottom plan view thereof;

FIG. 8 is a side perspective view of a second embodiment for a carton with handle showing our new design;

FIG. 9 is a front view thereof; and,

FIG. 10 is a bottom plan view thereof, the remaining views of the carton with handle of FIGS. 8-10 being identical to FIGS. 3-6.

The broken line showing is for illustrative purposes only and forms no part of the claimed design.
